(57) **CLAIM**

The ornamental design for a potty-training aid, as shown and described.

DESCRIPTION

FIG. 1 is a PERSPECTIVE view of a design for the potty-training aid, showing my new design;

FIG. 2 is a FRONT view thereof;

FIG. 3 is a BACK view thereof;

FIG. 4 is a SIDE view of thereof;

FIG. 5 is a SIDE view thereof;

FIG. 6 is a TOP view thereof;

FIG. 7 is a BOTTOM view thereof;

FIG. 8 is a SECOND PERSPECTIVE view thereof; and,
FIG. 9 is an EXPLODED view thereof.

The dashed broken lines shown in the drawings depict portions of the potty-training aid that form no part of the claimed design.
